UNITED STATES PATENT OFFICE.

DAVID C. DUNCAN, OF DULUTH, MINNESOTA.

GENERATOR.

Application filed August 9, 1923. Serial No. 656,556.

To all whom it may concern:

Be it known that I, DAVID C. DUNCAN, a citizen of the United States, residing at Duluth, in the county of St. Louis and State of Minnesota, have invented certain new and useful Improvements in Generators, of which the following is a specification, reference being had therein to the accompanying drawing.

10 This invention relates to acetylene gas generators and has special reference to that type known as low pressure portable generators comprising an upright water tank or container in which the necessary water for generating is carried, said container being open in the upper end thereof, and a vertically removable bell or gas tank, supporting internally thereof the cage or holder for the carbide, or "carbic cakes" as the briquetted carbide is commonly called.

15 Such generators are moved about from place to place by hand, or on vehicles, and are used in many classes of work; during the moving of which it is found that the vibration or motion will cause the water in the container to splash or surge out of the upper open end thereof, which is obviously objectionable in many respects.

20 To overcome this slushing out of the water in the container is the principal object of my present invention, while other objects and advantages of the peculiar construction will appear in the further description thereof.

25 Referring to the accompanying drawing forming part of this application and in which like reference characters indicate like parts:

30 Figure 1 is a central vertical section of an acetylene gas generator showing in elevation my anti-slushing device or baffle installed therein; while

35 Figure 2 is an enlarged top plan view of the improved baffle.

40 1 represents the cylindrical sheet metal water tank or container which is open at the top and has suspended therein the gas-bell 2, said bell being suspended upon the cross arm 3 ordinarily held in position upon the container by means of suitable wing nuts and hinged bolts 4 and 5 respectively. 6 represents the cylindrical back pressure valve which is installed adjacent the body portion of the gas bell 2 and ordinarily extends into the water in the container.

45 My improved baffle head is installed about

the body of the gas bell and the back pressure valve, preferably some little distance below the upper end of the container 1, within or adjacent the normal water level, and 50 comprises two spaced heads 7 and 8 of metal or wood. These heads are permanently spaced apart by suitable radially disposed division walls 9 and are permanently attached to the heads 7 and 8. The double 55 head thus formed is divided into two equal parts with the upper edges thereof turned down forming lugs 10, as it were, which are unitable by small bolts 11. The baffle has an axial hole 12 therein for the reception of the 60 body of the gas bell, and also a hole 13 therein into which the back pressure valve fits, so that the head may be separated before being placed about the gas bell and pressure valve, then drawn up tightly to fit same. An auxiliary cover 14 is provided for the hole 13, the halves of said cover being fastened to the upper face of the uppermost head of the baffle by suitable screw bolts 15 which are mounted in slotted holes in the baffle so that 65 they may be readily adjusted to more tightly fit the back pressure valve.

70 The baffle is made slightly smaller in diameter than the inside diameter of the container and the close fitting of same about the 75 gas bell and pressure valve is somewhat immaterial, though must be sufficiently so as to prevent a large volume of water passing same, and, in fact, either or both baffle heads 80 may be perforated if desired.

75 In practice such a device has proven exceedingly efficient, the annoyance of splashing out of the water out of the container in any considerable quantity being entirely done away with, as during the surging of 85 the container it is found that the water cannot objectionably splash out above the uppermost head of the baffle, as but little motion of water intermediate of the heads and the division walls can possibly take place, 90 thus adequately insuring against slushing over of the water in the container and yet does not prevent free discharge of the water from the container in the event of the latter being accidentally upset, the advantages of 95 100 which are well known to those versed in the art.

Having thus described my invention, what I claim and desire to secure by Letters Patent, is:

110 1. The combination with a gas generator comprising an upright cylindrical water

container, a gas bell suspended within said container, and an upright back pressure valve adjacent the gas bell, of a horizontally disposed anti-slushing baffle surrounding 5 said gas bell and back pressure valve, said baffle being separable diametrically of the gas bell and back pressure valve for convenient adjustment thereabouts.

2. The combination with a gas generator 10 comprising an upright cylindrical water container, a gas bell suspended within said container, and an upright back pressure valve adjacent the gas bell, of a horizontally disposed anti-slushing baffle surrounding 15 said gas bell and back pressure valve, said baffle being separable diametrically, and independently adjustable encircling means car-

ried by the baffle surrounding the back pressure valve.

3. In an acetylene generator an anti-slushing baffle comprising two concentrically mounted spaced heads having axial openings therethrough and radially disposed division walls intermediate of the heads acting as spacing means therefor and dividing said space into a plurality of compartments for the purpose described. 20 25

In testimony whereof I hereunto affix my signature in the presence of two witnesses.

DAVID C. DUNCAN.
